(57) **CLAIM**

The ornamental design for a headphone cup for headphones substantially as shown and described.

DESCRIPTION

FIG. 1 is a front perspective view of a left headphone cup for headphones.

FIG. 2 is a front elevation view thereof.

FIG. 3 is a rear elevation view thereof.

FIG. 4 is a left elevation view thereof.

FIG. 5 is a right elevation view thereof.

FIG. 6 is a top plan view thereof.

FIG. 7 is a bottom plan view thereof.

FIG. 8 is a rear perspective view thereof.

FIG. 9 is a front perspective view of a right headphone cup for headphones.

FIG. 10 is a front elevation view thereof.

FIG. 11 is a rear elevation view thereof.

FIG. 12 is a left elevation view thereof.

FIG. 13 is a right elevation view thereof.

FIG. 14 is a top plan view thereof.

FIG. 15 is a bottom plan view thereof; and,

FIG. 16 is a rear perspective view thereof.

The broken lines depict portions of the headphone cup for headphones that form no part of the claimed design.

1 Claim, 12 Drawing Sheets
